CURTAIN ROD

Max Barnett, Brooklyn, N. Y.

Application February 9, 1948, Serial No. 7,182

4 Claims. (Cl. 223—105)

1

This invention relates to a removable adapter for curtain rods and has for its primary object the provision of a functionally and structurally improved and simplified adapter which will aid in threading curtain rods through the hems of the curtains. A widely used type of curtain rod is made of a strip of thin metal having turned over margins, the rods being of general flat channel formation. It is a very slow and difficult task to feed such rods through the hems of newly laundered curtains, particularly those made of loosely woven fabrics as the ends of the rods catch the threads of the fabric, and unless great care is taken, threads become broken or spread apart by the rod which may then work its way through the side of the hem. When the curtain is nearly all threaded onto the rod, which operation requires the use of both hands, very often a considerable portion of the hem will slip over the opposite end of the rod and it is particularly difficult to guide the hem back again, due to the usual bend near the adjacent end of the rod. Accordingly, another object of the invention is to provide a novel adapter removably associated with one end of a curtain rod, thereby permitting the rod to be thrust rapidly and smoothly into the hem of a curtain. Another object resides in the provision of a retaining spring forming a part of the adapter for cooperating with the rod to preclude slippage of the adapter therefrom. The invention will now be described with the aid of the accompanying drawings wherein:

Fig. 1 is a perspective view of the right hand component of a curtain rod showing the removable adapter according to my invention with the leaf spring cooperating with the inside surface of the rod.

Fig. 2 is a perspective view of the adapter but showing the retaining leaf spring engaging the outside surface of the curtain rod.

Fig. 3 is an enlarged front elevation of the removable adapter.

Fig. 4 is a longitudinal sectional view taken on the line 4—4 of Fig. 3.

Fig. 5 is an end view of the adapter.

Fig. 6 is a sectional view taken through the line 6—6 of Fig. 4.

Fig. 7 is a front view of a preferred form of retaining clip or resilient looped pin, and

Fig. 8 is a view similar to Fig. 3 but with the channel of the head of the adapter covered up by an intervening bridge portion.

Illustrative of the embodiments disclosed the adapter 10 is formed of any suitable material, such as, aluminum, hard rubber, or plastic, and

is characterized by a reduced shank 11 having integral therewith the enlarged head 12 which is crown-shaped or rounded as shown. Shank 11 is shaped to removably fit into the channel of a common type of telescoping curtain rod generally denoted C so that shoulder 13 formed by the head and shank constitute stop means to limit insertion of the rod on the adapter which embodies the laterally spaced lips 14 defining channel 15 forming a continuation of slot 16 formed in shank 11. Channel 15 and slot 16 communicate and are disposed longitudinally of the adapter. One end 17 of a centilever leaf spring broadly designated S is disposed within channel 15 and is secured to head 12 by rivet 18.

Normally the major part of the intermediate arcuate portion 19 of spring S is disposed out of slot 16 (Fig. 4) and its terminal beaded or free arcuate part 20 is about fully out of relief gap 22 which communicates with slot 16.

It will be observed that the spaced lips 14 are undercut to provide notches 21 for receiving the curtain rod.

Prior to inserting the adapter on the rod the intermediate arcuate portion 19 of the leaf spring is manually moved towards shank 11, thus arranging portion 19 to be flush with the shank and bead 20 within gap 22, permitting the rod C to receive shank 11 and the intermediate portion 19 of the spring S frictionally and yieldingly engages the body of the rod to preclude accidental slippage of the adapter therefrom.

In moving the rod on the adapter, lips 14 overlap adjacent end of the rod to facilitate threading of both the adapter and the rod through the hem of the curtain.

In Fig. 1, spring S is confined within the curtain rod C to hold the adapter securely thereon while in Fig. 2 spring S is cooperating with the outside face of the rod for similarly holding the adapter on the rod. In either case, the adapter may be conveniently removed from the rod when desired and in either case the adapter conveniently serves as means adapted to be quickly threaded into the hem of the curtain as required and of course the spaced lips as 14 overlie and shield the end of the curtain rod to prevent the latter from catching the curtain.

A spring clip 25, shown in Figs. 1 and 7 is provided for removable attachment to the opposite end of the curtain rod to prevent the hem of the curtain from slipping off the rod before the latter is placed on its permanent supporting bracket.

The spring clip 25 is formed from a length of wire bent at approximately its center 27 so as to

form two legs 28 and 29 which engage each other for a short distance immediately adjacent the bend 27. Leg 28 which is adapted to be thrust through an opening in the curtain rod designed to receive a supporting bracket, is bent to form a short offset section 30 which overlies the top of the curtain rod and then the leg is formed into a straight section 31 which is sufficiently long to extend beyond the lower margin of the curtain rod. Leg 29 comprises a straight portion adapted to rest against the outer surface of the rod. Leg 29 is sufficiently long to reach the lower margin of the rod. Leg 29 is bent in the direction of leg 28 to form an offset portion 32 adapted to extend under and receive the lower margin of the rod. Terminal 33 is integral with the offset portion 28 and diverges from the rectilinear and opposing section 31 of the resilient pin 25 which is threaded into opening 34 for removably snapping or interlocking this pin with the rod or bar C.

For purposes of specification bead 20 may be considered as a reflexed portion fully receivable in clearing gap 22 when the intermediate arcuate part 19 of the retaining spring is manually urged fully within slot 16.

The embodiment according to Fig. 8 is along the lines of species shown in Fig. 3 except that the channel formerly defined by the spaced lips 14 has been eliminated and filled in to be flush with the body of the head of the adapter. Otherwise the form of Fig. 8 is along the lines of the embodiment illustrated in Fig. 4 and in Fig. 8 parts corresponding to those shown in Fig. 4 have been primed.

Various changes may be made in details of construction and arrangement of parts without departing from the spirit of the invention or sacrificing any of the advantages thereof inherent therein.

I claim:

1. An adapter for a hollow curtain rod comprising an externally rounded head having a longitudinally arranged channel, a shank smaller in width and thickness than said head and integrally extending therefrom and removably insertable in said rod and including a slot in communication and in alignment with said channel and disposed longitudinally of said shank and embodying an end remote from said head provided with a relief gap in communication with said slot, a cantilever leaf spring having one end arranged in said channel and having an intermediate portion in part normally out of said slot but removably receivable therein and including an arcuate terminal in

alignment with said gap and having its major portion normally projecting therefrom, said head and shank constituting a shoulder for limiting insertion of said shank into said rod, and means for securing the end of said spring in said channel, said arcuate terminal on insertion of said shank into said rod cooperating with the latter to shift said spring into said slot and said arcuate terminal into said gap.

2. An adapter for a hollow curtain rod comprising a crown shaped head having a longitudinally arranged channel, a shank smaller in width and thickness than said head and integrally extending therefrom and removably insertable in said rod and including a slot in communication and in alignment with said channel and disposed longitudinally of said shank and embodying an end remote from said head provided with a transversely arranged relief gap in communication with said slot, a cantilever leaf spring having one end arranged in said channel and having an intermediate portion at least in part normally out of said slot but removably receivable therein and including a beaded terminal in alignment with said gap and having its major portion normally disposed outside of said gap, said head and shank constituting a shoulder for limiting insertion of said shank into said rod, and means for securing the end of said spring in said channel, said beaded terminal on insertion of said shank into said rod cooperating with the latter to urge said spring into said slot and said terminal into said relief gap.

3. The adapter according to claim 2 wherein said head comprises spaced lips straddling said leaf spring and having aligned notches for receiving said rod.

4. The adapter according to claim 3 further characterized in that said lips are spaced at least in part from said shank and are disposed facing a surface of said shank opposite to said shoulder and extend beyond the latter.

MAX BARNETT.
